UNITED STATES PATENT OFFICE.

EVALD J. ENGMAN, OF SYRACUSE, NEW YORK, ASSIGNOR TO THE WILL & BAUMER COMPANY, OF SYRACUSE, NEW YORK, A CORPORATION OF NEW YORK.

HOISTING APPARATUS FOR CANDLE-FINISHING MACHINES.

1,344,445.

Specification of Letters Patent.

Patented June 22, 1920.

Application filed December 19, 1917. Serial No. 207,900.

To all whom it may concern:

Be it known that I, EVALD J. ENGMAN, a citizen of the United States of America, and resident of Syracuse, in the county of Onondaga, in the State of New York, have invented new and useful Improvements in Hoisting Apparatus for Candle-Finishing Machines, of which the following, taken in connection with the accompanying drawing, is a full, clear, and exact description.

This invention relates to certain improvements in hoisting apparatus adapted to be used in machines for finishing candles, and is somewhat similar to that set forth in my Patent No. 1,114,871, October 27, 1914, for raising and lowering the candle supporting carriage.

In the patent referred to, the carriage for drawing the candles through the finishing dies is started in its upward movement by a counterweight which is just sufficient to overbalance the carriage with the candles thereon exclusive of the resistance due to drawing the candles through the dies, said starting movement being utilized to operate a clutch as a part of a power-driven mechanism for positively raising the carriage through the remainder of its upward movement in drawing the candles through the dies.

It has been found, however, that the positive and uniform speed of feed of candles of different densities of the same or different materials, or under different temperatures, is objectionable in that it is liable to produce more or less imperfections, such as breaks or flaws, in the finished surface, and the main object of my present invention is to overcome these objections by controlling the speed of feed according to the nature of the material of which the candles are made, or rather according to the resistance of the dies in feeding the candles therethrough.

One of the specific objects is to feed the carriage with the candles thereon through its entire upward movement by weight-driven means and to control the speed of such movement in such manner that the speed will be reduced as the resistance to the draft of the candles through the dies increases.

A further object is to provide means for varying the maximum speed permitted to the upward movement of the carriage.

Other objects and uses relating to specific parts of the apparatus will be brought out in the following description.

In the drawings—

Figure 1 is a front elevation of a candle-finishing machine embodying the features of my invention.

Fig. 2 is a side elevation of the same.

Fig. 3 is an enlarged transverse sectional view through the die-supporting frame and one pair of dies, taken on line 3—3, Fig. 1.

Fig. 4 is an enlarged detail sectional view, partly in elevation, of the stop mechanism for holding the carriage against upward movement while the candles are being attached thereto, a portion of the carriage being shown in its extreme down position and in locking engagement with the stop bar.

Fig. 5 is an enlarged horizontal sectional view through the upper portion of the machine, taken on line 5—5, Fig. 1.

Fig. 6 is an enlarged detail sectional view, partly in elevation, of a part of the automatic clutch-releasing mechanism for stopping the carriage after the candles have been drawn through the dies.

Fig. 7 is a detail sectional view of the motor-driven worm and gear for operating the drum or sprocket for the carriage-controlling cable.

Fig. 8 is an enlarged longitudinal vertical sectional view of the die-supporting frame and dies therein, together with a portion of the carriage in its extreme down position wherein the candle-supporting rods project through the dies.

Fig. 9 is an enlarged horizontal sectional view taken on line 9—9, Fig. 1, showing underlying portions of the carriage and die-supporting frame, together with a portion of the hand lever for the variable speed gear shift.

Fig. 10 is an enlarged inverted plan of the primary clutch and its shifting means.

Fig. 11 is an enlarged detail sectional view of the same clutch, shown in Fig. 10.

The die-supporting frame —1— and dies —2—, together with the carriage —3— and guides —4— therefor, are substantially the same as shown in my patent referred to. That is, the supporting frame preferably consists of a hollow casing having a heating chamber —5— and a series of vertical tubes —6— extending therethrough from top to bottom for receiving and supporting

a corresponding number of the tubular dies —2—, said tubes being arranged in uniformly spaced relation so as to allow the heating agent in the chamber —5— to entirely surround the same.

The dies —2— are closely fitted within and extend through the tubes —6— and are provided with vertical openings therethrough tapered from bottom to top to compress and impart the desired finish to the surface of the candles in transit therethrough.

10 The chamber —5— is provided with an inlet —7— and an outlet —8— to permit the circulation of steam or other agent therethrough. This heating agent imparts its heat to the dies —2— for the purpose of softening the surface of the candles and permitting them to be more expeditiously 15 and highly finished as they are progressively drawn through the dies.

15 The guides —4— for the carriage —3— are secured at their lower ends to opposite ends of the frame or casing —1— and extend upwardly in parallelism to substantially the same height sufficient to allow the proper movement of the carriage —3— for drawing the candles from a position below 20 through and some distance above the dies, the upper ends of the guides being connected by a yoke or cap —9—.

25 The carriage —3— is provided with lower and upper pairs of hubs —10— movable along and upon the guides —4— and is also 30 provided at its lower end with pendent parallel rods —11— terminating in hooks —12— for attachment to the wicks, as —a—, of their respective candles —A—, the rods —11— being alined vertically with the openings in their respective dies —2— so as to 35 pass therethrough when the carriage is lowered to its extreme down position, in which position the hooks —12— are disposed in a plane below the lower ends of the dies where 40 they are accessible for the attachment of the candle wicks thereto by the operator.

45 A hand lever or link —13— is pivotally attached to the central upper portion of the carriage —3— to be engaged by the operator 50 for moving the carriage by hand if desired, as for example in drawing it down preparatory to placing the candles on the hooks —12—.

55 Suitable means is provided for temporarily locking the carriage in its extreme down position, and for this purpose I have provided an automatic locking member —14— pivotally mounted on one side of the carriage frame —3— to swing horizontally 60 into and out of a position directly under the lower end of a stop rod —15— which is secured at its upper end to the yoke —9— and extends downwardly therefrom parallel with the guide rods —4— to a point just above 65 the limit of downward movement of the

locking member —14— so that when the carriage is brought to its extreme downward position, the locking lever —14— will be rocked by a spring —14'— under the lower end of the stop rod —15— to temporarily hold said carriage against upward movement while the candles are being attached to the hooks —12—.

70 When the candles are properly attached to the carriage in the manner described, the stop lever —14— may be released or withdrawn by hand from under the lower end of the stop rod —15—, whereupon the carriage is raised by suitable mechanical means and its speed of movement controlled by mechanism hereinafter described.

Carriage-raising means.

75 The means for raising the carriage to draw the candles through the dies preferably comprises a chain or cable —16— having one end attached to the central upper portion of the carriage frame, as shown in Fig. 1, and its other end passed over a sprocket wheel or sheave —17— and attached to a weight —18—, Fig. 2, which is sufficiently heavy to draw the carriage upwardly against any ordinary resistance between the candles and dies, but is readily responsive to such resistance so that if the latter is excessive the upward lift of the carriage will be correspondingly slow, thereby preventing excessive tension on the candles which might produce flaws or breaks in the surface thereof, or if the resistance should be so great as to stop the carriage against the action of the weight, said carriage might readily be fed upwardly at the desired slow speed by means of the hand lever —13— with the assistance of the weight, it being understood that the weight —18— is carefully selected to just slightly overbalance the weight of the carriage with the candles thereon, and such resistance between the candles and dies as will avoid excessive rapidity of movement or overstraining of the candles in transit through said dies.

80 The sprocket wheel or sheave —17— is secured to a rotary sleeve —19— which in turn is journaled in suitable bearings —20— on the underside of the yoke —9— so as to bring the front face of the sprocket wheel in the vertical plane of movement of the carriage for direct upward pull thereon, said sleeve with the sprocket wheel thereon being rotated by the chain or cable —16— as the carriage and weight are raised and lowered.

Speed-control.

85 It is important in apparatus of this character that the movement of the candles through the dies shall be steady and sufficiently slow to give the desired finish without cracks or flaws, and at the same time to prevent overstraining of the candles in case

the resistance between the candles and dies is excessive during such movement, and in order that these results may be accomplished in a simple manner, I have provided what 5 may be termed a motor-driven controller for preventing the feed of the candles above a predetermined speed and allowing them to be fed at a slower speed without affecting the speed of the controlling motor.

10 As illustrated, this speed-controlling mechanism comprises a clutch collar —21— feathered or splined upon the inner end of the sleeve —19— so as to move axially into or out of engagement with a companion 15 clutch section —22— which is secured to a revolute shaft —23—, as shown more clearly in Fig. 5.

This shaft —23— extends coaxially of and loosely through the sleeve —19— and is 20 journaled in bearings —20— on the under side of the overhead support or yoke —9— for receiving and supporting a clutch collar —24— and a pair of gears —25—, said shaft being held against axial movement by the 25 clutch section —22— and a collar —26— both of which are tight on the shaft and engage opposite ends of one of the bearings —20—.

When the carriage is at its extreme limit 30 of downward movement in which it is held by the detent —14— against the action of the weight —18—, the clutch members —21— and —22— are disengaged, as shown in Fig. 5, to allow free rotation of the shaft —23— independently thereof, but are thrown into engagement with each other immediately upon the beginning of the upward movement of the carriage by said weight, and in order that this interengagement 35 of the clutches may be effected automatically, the clutch section —21— is provided with a cam —27— adapted to ride against the end of a pivoted shifting member —28— on the adjacent bearing —20—, Fig. 10, as said collar is rotated in the direction indicated by the arrows in the same figure, at the beginning of the lifting movement of the carriage by the weight —18—, thereby establishing a locking connection 40 between the cable-driven sleeve —19— and shaft —23— and causing said shaft to be driven by the same weight which lifts the carriage, the clutch teeth being preferably of the ratchet type for quick interlocking 45 engagement by slight relative rotation and are beveled in such manner as to allow them to slip in case the clutch member —21— on the weight-driven sleeve should revolve at a slower speed than its companion clutch 50 member.

The clutch-shifting member —28— is normally held by a spring —29— against a stop shoulder —30— on the bearing —20— to limit its movement in the direction of 55 movement of the collar during the raising

of the carriage, but is free to move in the opposite direction against the action of the spring when the direction of motion of the collar is reversed by the downward movement of the carriage without closing the 70 clutch, it being understood that the spring —29— is comparatively light and of just sufficient tension to return the shifting member —28—.

These clutch members usually remain in 75 engagement during the entire upward movement of the carriage in drawing the candles through their respective dies, but are automatically disengaged when the carriage reaches the limit of its upward movement. 80

For this latter purpose, the clutch collar —21— is provided with an annular groove for receiving the forked arms of a shifting member —31— which is secured to a sliding rod —32— on the bearings —20— 85 as shown more clearly in Fig. 10, one end of said rod being extended into proximity to the stop rod —15—, as shown in Fig. 6, and is bifurcated to receive one end of a bell-crank lever —33—, the latter being 90 pivoted at —34— to the adjacent bearing —20— and has its other arm engaged in a slot —35— in the upright stop bar —15—.

The bar —15— has a slight endwise or vertical movement sufficient to operate the 95 bell-crank lever —33— and rod —32— to disengage the clutch member —21— from its companion clutch —22— and is provided with a collar —36— adjustably secured thereto by set screw —37— and adapted to project into the path of upward movement of one of the hubs —10— on the carriage as shown more clearly in Fig. 2, said collar —36— being so adjusted that as soon as the candles are drawn entirely 100 through and slightly above their respective dies, the adjacent hub —10— on the carriage will engage the under side thereof, thereby lifting the rod —15— to operate the bell-crank lever —33— and rod —32— sufficiently 110 to disengage the clutch member —21— from its companion clutch —22—, thereby releasing the sleeve —19— and sprocket wheel —17— from connection with the shaft —23—. 115

Further upward movement of the carriage is limited by a stop collar —38— on the rod —15— adapted to engage the under side of a stationary part —39— of the overhead support or yoke —9—. 120

The carriage is held in its extreme up-position by the weight —18— at the will of the operator to allow ample time for the removal of the finished candles —A— from their supporting hooks —12—, whereupon 125 the carriage may be returned to its extreme down position by the hand lever —13— against the action of the weight —18— ready to receive another set of candles which are to be finished. 130

During this downward movement of the carriage, the rod —15— is free to return to its normal position by its own weight, but is limited in its return movement by another stop —38— similar to the stop —38— and adapted to engage the upper face of the stationary part —39—.

When the carriage is thus brought to the limit of its downward movement, the detent 10 —14— is rocked by spring —14'— to a position directly under the lower end of the rod —15— so that when the carriage is released, it will be moved upwardly a short distance by the weight, thereby carrying the 15 rod —15— with it until the latter is limited by the engagement of the shoulder —38— with the under face of the stationary part —39—, it being understood that during this time the clutch member —21— remains in its 20 open position and that the arm of the bell-crank lever adjacent the shifting rod —32— is free to play in the slot in the end thereof, or until said rod is shifted endwise by the rotation of the cam —27— against the shifting member —28—.

A spring-operated friction stop —40— is spring-pressed into engagement with notches in the shifting rod —32— to temporarily hold the latter and clutch member 30 operated thereby in either of its shifted positions.

The clutch member —24— which is the direct means for controlling the speed of rotation of the shaft —23— and consequently 35 the speed of upward movement of the carriage as the candles are being drawn through the dies is feathered upon said shaft to move into and out of engagement with a companion clutch section on the adjacent end of 40 the hub of the gears —25—, which gears are preferably made integral, but of different diametral pitch to permit the shaft to be rotated at different speeds in a manner hereinafter described, said clutch section —24— 45 being normally held in engagement with its companion by a coil spring —41— surrounding the shaft and having one end engaged with said clutch member and its other end engaged by an adjustable collar —42— 50 also mounted on the shaft to regulate the tension of the spring.

Another collar —43— is secured to the shaft at the opposite end of the hub of the gears —25— to coöperate with the clutch collar —24— in normally holding the gears —25— against axial movement.

The gears —25— are driven by one or the other of a pair of integrally connected pinions —44— which are slidable on a countershaft —45— by means of a shifting lever —46— on the end of an upright rod —47— having its lower end connected to the hub of a hand lever —48—.

This hand lever is movable about a

toothed rack —49— on the die case 1, Figs. 65 2 and 9, to temporarily hold the gears —44— in their adjusted positions.

The active portions of the gears —44— are spaced apart a distance greater than the combined width of the gears —25— to allow said pinions to be shifted to a neutral position or at opposite ends of the gears —25—, or either pinion may be shifted into engagement with its corresponding gear as may be desired to impart the proper speed 75 to the shaft —23—.

The countershaft —45— is journaled in suitable bearings —50— forming a part of a supplemental overhead frame —51— which also carries an electric motor —52— having 80 its armature shaft provided with a worm —53— engaging a worm wheel —54— on the countershaft —45— for causing said countershaft and pinions thereon to rotate at a relatively slow speed, while the relative 85 sizes of the pinions —44— and gears —45— cause the shaft —23— to rotate at a still slower speed.

The clutch teeth between the collar —24— and hub of the gears —25— tend to transmit 90 motion from the shaft —23— to said gears, while either pinion —44— meshing with its companion gear —25— drives said gears in the same direction.

It is now evident that when the motor is 95 in action and one or the other of the pinions in mesh with its corresponding gear —25—, said gears will be driven at a constant, but slow, speed and being loose on the shaft may turn freely independently thereof, or 100 while the carriage is at rest, thus permitting the motor to operate continuously.

It is also evident that as soon as the carriage is released by the tripping of the detent —14—, it will be drawn upwardly by 105 the weight —18—, thereby throwing the clutch members —21— and —22— into engagement through the medium of the cam —27— to cause rotation of the shaft —23—, but owing to the interlocking engagement 110 of the clutch member —24— on said shaft with the adjacent clutch face on the hub of the gears —25—, the speed of movement of the carriage will be thereby retarded to that of the gears —25—.

On the other hand, if the resistance to the draft of the candles through the dies should be excessive or sufficient to reduce the speed of upward movement of the carriage, it would not interfere in any way with the 120 free constant rotation of the gears —25— by reason of the specific arrangement of the teeth between clutch —24— and hub of said gears which allows said teeth to slip one by the other, or if the resistance to the passage 125 of the candles through the dies should be sufficient to stop the carriage, the same slipping effect between the gears —25— and

clutch member —24— would take place, in which case the carriage might be moved upwardly by means of the lever —13—.

This latter condition, however, is extremely rare and is only mentioned to show that provision is made therefor.

As previously explained, as soon as the carriage reaches the limit of its upward movement and the candles have been withdrawn from the dies, further upward movement of the carriage is stopped by the engagement of one of the upper hubs —10— with the collar —36—, thereby operating the bell-crank lever —33— and rod —32— to disengage the clutch section —21— from its companion —22—, thereby disconnecting the sprocket wheel —17— from the shaft —23—, while at the same time the stop —38— engages the stationary abutment —39— to further limit such upward movement under the action of the weight —18—.

When the finished candles have been removed from their respective supports —12—, the carriage may be returned to its initial starting position ready to receive another set of candles to be operated upon in the manner previously described.

Aside from establishing a driving connection between the constantly driven gears —25— and shaft —23— when the clutch —21— is disengaged from its companion —22— and its additional function of limiting the speed of rotation of said shaft by the carriage-operating weight when said clutch members —21— and —22— are engaged and thereby preventing excessive speed of feed of the candle-supporting carriage, a still further function of the slip drive is to steady the upward movement of the carriage, particularly in preventing a sudden jerk incidental to overcoming the inertia of the carriage and parts carried thereby during the starting operation, or while the cam —27— is shifting the clutch member —21— into engagement with its companion —22—, because under those conditions the speed of rotation of the shaft, due to said inertia, would be temporarily slower than that of the constantly driven gears —25— and would cause the clutch member —24— to slip relatively to its companion clutch face on the hub of said gears, which would also compensate for any imperfect engagement between the teeth of the clutch members —21— and —22— during such starting movement.

What I claim is:

1. In a candle finishing machine the combination of a vertically reciprocatory candle carrier adapted to be moved downwardly at will, mechanical retracting means including a rotary element for raising the carriage, a separately rotatable element, means including a clutch for transmitting

motion from the first named element to the second named element, an additional rotary element, means including a clutch for transmitting motion from the second named element to the additional element and means for driving said additional element at a constant relatively slow speed for preventing excessive speed of movement of the carriage raising means.

2. In a candle finishing machine the combination of a vertically reciprocatory candle carrier adapted to be moved downwardly at will, mechanical retracting means including a rotary element for raising the carriage, a separately rotatable element, means including a clutch for transmitting motion from the first named element to the second named element, an additional rotary element, means including a clutch for transmitting motion from the second named element to the additional element and means for driving said additional element at a constant relatively slow speed for preventing excessive speed of movement of the carriage raising means, the second named clutch being spring pressed to its operative position.

3. In a candle finishing machine the combination of a vertically reciprocatory candle carrier adapted to be moved downwardly at will, mechanical retracting means including a rotary element for raising the carriage, a separately rotatable element, means including a clutch for transmitting motion from the first named element to the second named element, an additional rotary element, means including a clutch for transmitting motion from the second named element to the additional element and means for driving said additional element at a constant relatively slow speed for preventing excessive speed of movement of the carriage raising means, the second named clutch being free to slip in case the carriage is raised at a slower rate of speed than that permitted by the constant speed of movement of said additional rotary element.

4. In a machine for finishing candles the combination of a finishing die, weight-operated means including a rotary element for drawing a candle through the die, an additional rotary element, means for driving said additional rotary element at a constant speed, and means including a clutch for transmitting motion from one of said rotary elements to the other, said clutch being free to slip in case the speed of rotation of the first named rotary element is less than that permitted by the constant speed of the second named rotary element.

5. In a candle finishing machine the combination of a die, a vertically reciprocatory candle carrier for drawing a candle through the die, a rotary wheel, a cable attached to the carrier and passing over said wheel, a

6
weight attached to the cable for revolving the wheel and raising the carrier, a rotary shaft, means including a clutch for transmitting motion from said wheel to the shaft, 5 as the carrier is raised, a rotary gear and driving connections between said shaft and gear including a clutch.

6. In a candle finishing machine the combination of a finishing die, a vertically reciprocating candle carrier for drawing the candle through the die, a rotary shaft, a sheave loosely mounted coaxial with the shaft, a cable passed over the sheave and having one end connected with the carrier 10 and its other end provided with a weight for raising the carrier, means including a clutch for transmitting motion from the sheave to the shaft, a loose gear coaxial with the shaft, means for driving the gear 15 at a constant speed and clutch connections between the shaft and gear capable of slipping in case the shaft should be driven at 20 a slower rate of speed than that of the gear.

7. In a candle finishing machine the combination of a die, a vertically reciprocating 25

candle carrier for drawing a candle through the die, a rotary shaft, a wheel coaxial with the shaft and rotatable independently thereof, a cable passed over the wheel and having one end connected to the carrier, a weight attached to the opposite end of the cable for raising the carrier, means including a clutch for transmitting motion from the wheel to the shaft, a gear loose on the shaft and provided with a clutch face, a clutch feathered on the shaft and spring pressed axially into engagement with the clutch face of the gear and means for driving the gear at a constant speed, said clutch being free to slip relatively to the clutch face of the gear in case the shaft should be rotated at a speed less than that of the gear.

In witness whereof I have hereunto set my hand this 8th day of December, 1917. 45

EVALD J. ENGMAN.
